DESIGN FOR A BOTTLE

John F. Watson, Maplewood, N. J., assignor to The
Borden Company, New York, N. Y., a corpora-
tion of New Jersey

Application October 7, 1938, Serial No. 80,304

Term of patent 14 years

To all whom it may concern:

Be it known that I, John F. Watson, a citizen of the United States, residing in Maplewood, county of Essex, State of New Jersey, have invented a new, original, and ornamental Design for a Bottle, of which the following is a specification, reference being had to the accompanying drawing, forming a part thereof.

In the drawing, Figure 1 is a side elevation of a bottle embodying my new design.

Figure 2 is a top plan view of the bottle shown in Figure 1.

Figure 3 is a side elevation of the bottle rotated 45° from the position in Figure 1, and

Figure 4 is a horizontal section of the bottle taken on the line 4—4 of Figure 1.

The bottle is substantially square in cross-sections throughout approximately its lower two-thirds having four slightly concave sides, and is circular in cross section throughout approximately its upper one-third.

I claim:

The ornamental design for a bottle, as shown and described.

JOHN F. WATSON.
